(57) **CLAIM**

The ornamental design for an alignment bracket, as shown and described.

DESCRIPTION

FIG. 1 is a perspective view of an alignment bracket in accordance with the present invention;

FIG. 2 is a side view of the alignment bracket of FIG. 1;

FIG. 3 is an end view of the alignment bracket of FIG. 1;

FIG. 4 is an opposite end view of the alignment bracket of FIG. 1;

FIG. 5 is an opposite side view of the alignment bracket of FIG. 1;

FIG. 6 is a top view of the alignment bracket of FIG. 1; and,

FIG. 7 is a bottom view of the alignment bracket of FIG. 1. The broken line portions illustrate environmental features that form no part of the claimed design and unshaded surfaces bound on all sides by broken lines form no part of the claimed design.

1 Claim, 3 Drawing Sheets
